Patented Oct. 17, 1922.

INVENTOR
Irvin H. McFarland.

BY *William J. Jackson*
ATTORNEY.

UNITED STATES PATENT OFFICE.

IRVIN H. McFARLAND, OF PHILADELPHIA, PENNSYLVANIA.

KNOCKDOWN BUILDING CONSTRUCTION.

Application filed July 22, 1921. Serial No. 486,766.

To all whom it may concern:

Be it known that I, IRVIN H. McFARLAND, a citizen of the United States, residing at the city of Philadelphia, county of Philadelphia and State of Pennsylvania, have invented 5 certain new and useful Improvements in Knockdown Building Construction, of which the following is a specification.

This invention generally stated relates to 10 building construction and has more particular relation to an attachment employed in building construction of knock-down character.

The leading object of the present invention 15 may be said to be the providing of a simple, efficient and comparatively inexpensive attachment employed for temporarily securing together parts of building construction of knock-down type whereby the parts 20 may be readily and expeditiously put together and taken apart and still possess a maximum degree of rigidity in assembled position. Other and further objects relate to the provision of general details of construction and arrangement and combination 25 of parts for attaining the results sought by the leading object.

The invention consists of the improvements hereinafter described and finally 30 claimed.

The nature, characteristic features and scope of the invention will be more fully understood from the following description taken in connection with the accompanying 35 drawings forming part hereof, and in which:

Fig. 1, is a top or plan view, partly in elevation and partly in section, of a post and a rail about to be assembled,

Fig. 2, is a view in side elevation, partly 40 sectioned, of the parts shown in Fig. 1, in assembled position,

Fig. 3, is a face view of a post,

Fig. 4, is a rear elevational view of the lock-plates shown in Figs. 1 and 2,

Fig. 5, is a view in cross section of the lock-bolt shown in Figs. 1 and 2, and

Fig. 6, is a view of the lock-bolt looking toward the left hand side of Fig. 5.

For the purpose of illustrating my invention I have shown in the accompanying drawings one form thereof which is at present preferred by me, since the same has been found in practice to give satisfactory and reliable results, although it is to be understood that

the various instrumentalities of which my 55 invention consists can be variously arranged and organized and that my invention is not limited to the precise arrangement and organization of the instrumentalities as herein shown and described. 60

While the attachment about to be described is applicable to various forms of building construction it is particularly adapted for use in erecting partitions calculated for temporary use. In practice one 65 part of my improved attachment is carried by an upright or post and a companion part by a horizontal rail. Obviously the number of posts and rails vary with the type of work to be done and it will be understood that as 70 many faces of a post are equipped with my attachment as there are rails to be attached. However, since each part is a duplicate of another I have shown in the drawings for 75 illustrative purposes the upper end of a rail. In the drawings 10 designates an upright or post, usually of wood, at least one face of which is countersunk to accommodate a plate 11, secured to said post as by screws 12. Plate 11 is provided with a substantially T- 80 shaped opening therethrough, the upper or enlarged end being designated 13; the lower end being narrow or slot-like and in communication with the enlarged end and being designated 14. Upon the rear face of such 85 plate, one upon each side of said slot 14, are ribs 15 which taper inwardly from the upper to the lower portion of said slot and form guides for a lock-bolt hereinafter referred to. The opening and ribs are formed by removing some of the plate material to provide the opening and then bending the material immediately surrounding portions of the opening thus made to provide the ribs. 90

The post 10 is cut away as at 16 to the rear 95 of plate 11. Adapted to be secured between a pair of posts 10, equipped with plates as above described, is at least one horizontal rail 17 each end of each being equipped with a lock-bolt about to be described. In practice 100 each bolt comprises a head 18 and a screw-threaded shank 19 preferably formed integral with one another although this is not essential. The head is of rectangular configuration and of a size to pass readily through opening 13 of plate 11. The inner face of said head is flat and is provided with parallel, spaced grooves 20 for engaging

with the tapered ribs 15. These grooves are also tapered, see Fig. 5, so that the head be properly aligned with said ribs. In other words the head is scored to provide grooves 5 with parallel walls and inclined bottoms to engage the ribs. The shank 19 has screw-threaded relation with rail 17. In assembling the parts the leads 18 of a rail are inserted through the openings 13 of plates 11 10 of a pair of posts and the grooves of the heads caused to engage with the ribs of the plates 11. By pressing downward upon the rail the heads travel along the ribs 15 and gradually bind with respect thereto thus 15 bringing the ends of a rail in snug abutting relation with the faces of a post, the heads being accommodated within spaces 16. Since the heads have screw-threaded relation with a rail it is possible to adjust the 20 heads toward or away from the rail ends when desired. Such a construction of parts is simple and inexpensive to make, enables a partition or the like to be readily assembled and taken down and affords a maximum degree 25 of rigidity of assembled parts.

It will now be apparent that I have devised a novel and useful construction which embodies the features of advantage enumerated as desirable in the statement of the 30 invention and the above description and while I have in the present instance shown and described the preferred embodiment thereof which has been found in practice to give satisfactory and reliable results, it 35 is to be understood that the same is susceptible of modification in various particulars without departing from the spirit or scope of the invention or sacrificing any of its advantages.

40 What I claim is:

1. In combination a vertical member and a horizontal member adapted for detachable application thereto of which the first mentioned member is provided with an apertured plate the rear face of said plate being provided with inclined ribs which aperture and ribs are formed by removing some of the plate material to provide the aperture and bending the material immediately surrounding portions of said aperture thus made to provide the ribs and of which the last mentioned member is provided with a head for passage through said apertured plate, a face of said head being scored to 55 provide grooves with parallel walls and inclined bottoms to engage said ribs.

2. In combination a vertical member and

a horizontal member adapted for detachable application thereto of which the first member is provided with a plate having a substantially T-shaped opening therethrough, said plate having inclined ribs upon the rear face thereof, which opening and ribs are formed by removing some of the plate material to provide the opening and bending the material immediately surrounding portions of said opening thus made to provide the ribs and of which the last mentioned member is provided with a head for passage through said opening, said head being scored to provide grooves with parallel walls and inclined bottoms to engage said ribs.

3. In combination a vertical member and a horizontal member adapted for detachable application thereto of which the first mentioned member is provided with a rectangular, cut-away portion, a rectangular plate fitted within said cut-away portion which plate has a substantially T-shaped opening therethrough and is provided with inclined ribs upon the rear face thereof said ribs being disposed in a plane at right angles to the vertical plane of the plate and projecting into said cut-away portion, said opening and ribs being formed by removing some of the plate material to provide the opening and bending the material immediately surrounding portions of the opening thus made to provide the ribs, and of which the last mentioned member is provided with a head for passage through the plate opening into said cut-away portion, a face of said head being scored to provide grooves with parallel walls and inclined bottoms to engage said ribs.

4. In combination a pair of members adapted to be detachably fitted together of which one of said members has secured thereto a plate having an opening therethrough and having inclined ribs upon its rear face, which opening and ribs are formed by removing some of the plate material to provide the opening and bending the material immediately surrounding portions of the opening thus made to provide the ribs and of which the other of said members has secured thereto a head for passage through the plate opening said head being scored to provide grooves with parallel walls and inclined bottoms to engage said ribs.

In testimony whereof, I have hereunto signed my name.

IRVIN H. McFARLAND.
